ABSTRACT: A gas-fired burner includes a lower bowl and a flared inlet conduit communicating with the interior of the bowl. An upper bowl is adapted for stacking assembly with the lower bowl and is provided with a serrated outer edge so that when the upper and lower bowls are assembled the serrated edge of the upper bowl and the inner wall of the lower bowl define a multiplicity of gas burner ports circumferentially spaced about the bowl assembly. This design substantially eliminates flashback and has turndown characteristics between about 1,000 Btu. and 30,000 Btu. The burner assembly can be included in a vertically assembled chicken brooder which includes a spaced heat shield and overlapping canopy which uniformly distribute the heat by reflection downward to the surrounding nesting area.

GAS-FIRED BURNER AND BROODER ASSEMBLY**BACKGROUND OF THE INVENTION**

This invention relates to a gas-fired burner chicken brooder assembly. More particularly, the invention relates to a gas-fired burner which substantially eliminates flashback and is capable of delivering a wide range of heat.

In raising baby chickens it is important that they be supplied with the correct amount of heat uniformly distributed throughout the nesting area. If the brooder provides unequal heat distribution in the nesting area, the chicks invariably attempt to crowd to the most comfortable area causing a likelihood of increase in chick mortality. In a particular brood of chicks, there are always some chicks which are weaker than others. The weaker chicks are pressed aside by the stronger chicks and frequently unable to reach food or water. Under such conditions, an increase in chick mortality is likely.

In addition to supplying uniform heat throughout the nesting area, it is important that a gas-fired brooder have good turndown characteristics and be capable of delivering a wide range of heat, depending on the ambient temperature of the nesting area. In addition, it is important that the gas-fired burner have minimum flashback for safety purposes.

DESCRIPTION OF THE INVENTION

I have now developed a gas-fired burner and chicken brooder assembly which is capable of supplying a wide range of heat and distributing this heat in a substantially uniform manner throughout the nesting area. In addition, the burner is substantially free from flashback which renders the burner assembly and chicken brooder exceptionally safe for use in raising chicks and avoids disturbing the fowl.

An object of this invention is to provide a gas-fired burner which is capable of supplying a wide range of heat.

Another object of this invention is to provide a gas-fired burner which is substantially free from flashback.

A further object of this invention is to provide a gas-fired burner and chicken brooder assembly which is capable of supplying a wide range of heat and distributing the heat in a uniform manner throughout the nesting area.

Other objects and advantages will become apparent from the following description taken in conjunction with the accompanying drawings wherein:

FIG. 1 is an exploded side elevation view, shown partially in section, of the gas-fired burner and chicken brooder assembly;

FIG. 2 is a side elevation view, shown partially in section, of the assembled gas burner and chicken brooder;

FIG. 3 is a sectional view of the gas-fired burner assembly;

FIG. 4 is a sectional view of the gas-fired burner assembly taken along the line 4-4 of FIG. 3;

FIG. 5 is a closeup top plan view of the triangle-shaped gas burner ports circumferentially distributed about the stacked assembly of upper and lower burner bowls;

FIG. 6 is a sectional view taken along the line 6-6 of FIG. 5.

DESCRIPTION OF THE INVENTION

In accordance with this invention, the gas-fired burner assembly includes a lower bowl and a gas inlet conduit communicating with the interior of the lower bowl in which the burner gas and air are mixed. The inlet conduit is flared to provide an increased cross section at the point of communication with the lower bowl in order to produce a venturi effect on the incoming gas-air mixture. Also included in the assembly are means for controlling the supply of gas through the conduit and an upper bowl adapted for stacking assembly with the lower bowl which is provided with a serrated outer edge so that when the upper and lower bowls are assembled the serrated edge of the upper bowl and the inner wall of the lower bowl define a multiplicity of gas burner ports circumferentially spaced or distributed about the bowl assembly. This construction substantially eliminates flashback and provides the burner with turndown characteristics ranging between about 1,000 B.t.u. and about 30,000 B.t.u. A pilot assembly

communicates with the interior bowl assembly for ignition purposes.

This invention also contemplates a combination of the gas-fired burner assembly with other elements in vertical assembly to form a chicken brooder. The chicken brooder can be formed by vertically assembling over the burner a heat shield, and a first spacer separating the upper bowl from the heat shield. Also included are a heat reflective canopy, a second spacer separating the heat shield from the canopy, and fastening means for maintaining the brooder in vertical assembly. When the burner is lit, the brooder assembly will deliver heat in a range between about 1,000 B.t.u. and about 30,000 B.t.u. which is uniformly distributed by reflection from the heat shield and canopy to the surrounding nesting area so that a substantially uniform temperature is maintained.

PREFERRED EMBODIMENTS

Referring now to the drawings, FIG. 1 shows the gas-fired burner and other elements making up the chicken brooder in disassembled form and FIG. 2 shows the burner and chicken brooder assembled. The burner assembly includes lower burner bowl 33 provided with gas inlet conduit 34 communicating with the interior of the lower bowl. The inlet conduit

is provided with a venturi or increased diameter at the point of communication 17 with lower bowl 33. Burner pan 37 is positioned beneath lower bowl 33 for collecting dust and is separated therefrom by pipe spacer 36. Burner pan 37 is fastened to spacer 36 by washer 38 and nut 39. Valve assembly 40 controls gas flow into inlet conduit 34. Control valve 40 connects to gas fed pipe 41 and this assembly attaches to hover or canopy 10 by means of linkage 42 (shown in more detail in FIG. 2). Gas inlet conduit 34 is provided with bell-shaped hood 35.

Upper bowl 30 is adapted for stacking assembly with lower bowl 33 and is provided with a serrated outer edge 12. When upper bowl 30 and lower bowl 33 are assembled, serrated edge 12 of upper bowl 30 and inner wall 18 of lower bowl 33 define a multiplicity of triangular-shaped gas burner ports 31 circumferentially distributed about the bowl assembly. The gas is ignited just above these burner ports.

Pilot assembly 43 is provided with air inlet openings 44 and gas-connecting pipe 45 (gas source not shown) which communicates with the interior of the bowl assembly. This assembly will relight the gas flame if it is momentarily extinguished and thus improve the safety of the burner.

Heat shield 23 is separated from upper bowl 30 of the burner assembly by hollow spacer 20 which is provided with air inlet openings 21 and connects at its lower end to bowl 30 and at its upper end to heat shield 23 by means of centering washer 22. Canopy 10 is separated from heat shield 23 by hollow spacer 24 provided with air inlet openings 25 and 26 which connects at its lower end to heat shield 23 and at its upper end through centering washer 27 to canopy 10. Cover 13 is positioned on top of canopy 10 and connects the remainder of the assembly through angle bar 14 to support 19. The brooder is conveniently vertically assembled and strung together by threaded bar 15 which passes downwardly through the center of each of the members shown in FIGS. 1 and 2. The assembly is held together by wing nut 16 and nuts 11 and 39 engaging bar 15.

FIGS. 3 and 4 show the details of the gas-fired burner assembly construction. As can be seen from FIG. 3, the gas-air mixture enters in the direction of the arrows through conduit 34 and is then distributed (in the direction of the arrows) equally to each of triangular-shaped burner ports 31. By this arrangement, the burner is capable of burning with a blue flame and substantially eliminates flashback. The burner assembly is thus safer and does not disturb the flocks of fowl. A supplementary source of air is supplied to the burner by way of air inlet openings 21, 25 and 26 and the chimney effect produced by the rising air in hollow spacers 20 and 24 (shown in the assembled brooder of FIG. 2).

FIGS. 5 and 6 show the details of construction of the triangular-shaped gas burner ports 31 formed by serrated edge 12 of bowl 30 when placed in stacked assembly with inner wall 18 of lower bowl 33.

Most good burners are of cast metal with a raised port to provide a better airflow around the expelled gas jet. The raised part must be drilled. According to my invention drilling is not required to form the burner ports and upper bowl 30 and lower bowl 33 can be easily formed by a simple stamping operation resulting in a lower cost in manufacturing the burner assembly. Moreover, this burner and brooder assembly are capable of operating satisfactorily under extremely dusty conditions.

Although the present invention has been described in conjunction with preferred embodiments, it is to be understood that modifications and variations may be resorted to without departing from the spirit and scope of the invention as those skilled in the art will readily understand.

I claim:

1. A vertically assembled, gas-heated chicken brooder which comprises:
 a lower burner bowl;
 a gas inlet conduit communicating with the interior of the lower bowl in which the burner gas and air are mixed, said inlet conduit provided with an increased cross section at the point of communication with the lower bowl;
 means for controlling the supply of gas through the conduit;
 a pilot assembly communicating with the interior of the lower bowl;
 an upper burner bowl adapted for stacking assembly with the lower bowl and provided with a serrated outer edge so that when the upper and lower bowls are assembled the serrated edge of the upper bowl and the inner wall of the

5

lower bowl define a multiplicity of gas burner ports circumferentially spaced about the bowl assembly; a heat shield positioned above the stacked bowl assembly; a first spacer separating the upper bowl from the heat shield;

a heat reflective canopy positioned above the heat shield; a second spacer separating the heat shield from the canopy; and

fastening means for maintaining the brooder in vertical assembly, whereby burner flashback is substantially eliminated and the brooder will deliver heat in a range between about 1,000 B.t.u. and about 30,000 B.t.u. which is uniformly distributed by reflection from the heat shield and canopy to the surrounding nesting area.

2. A chicken brooder in accordance with claim 1 wherein the gas burner ports are triangular-shaped.

3. A chicken brooder in accordance with claim 2 including a burner pan positioned beneath the lower burner bowl for collecting dust.

4. A chicken brooder in accordance with claim 3 wherein the fastening means includes a support bar extending vertically through each member of the assembly to maintain said members in vertical assembly.

5. A chicken brooder in accordance with claim 4 wherein the first and second spacers are hollow and are provided with air inlets to cause a chimney effect in the brooder assembly.

6. A chicken brooder in accordance with claim 4 wherein the canopy is provided with a cover.

7. A chicken brooder in accordance with claim 6 wherein the supporting bar is threaded and is provided with nuts for maintaining the vertical assembly.
